(57) **CLAIM**

The ornamental design for a packaging box, as shown and described.

DESCRIPTION

FIG. 1 is a top, front and right side perspective view of a packaging box showing my new design;

FIG. 2 is a top, rear and left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is a top, front and right side perspective view thereof in a state where a cover box is detached from a body box and aligned with the body box;

FIG. 10 is a top, front and left side perspective view thereof in a state where the cover box is detached from the body box and aligned with the body box;

FIG. 11 is a top, front and left side perspective view thereof in a using state where the cover box is turned over and the body box is stacked therein, and the slope of the cover box and the slope of the body box are matched;

FIG. 12 is a top, front and left side perspective view thereof in a using state where the cover box is turned over and the body box is stacked therein, and the slope of the cover box and the slope of the body box are opposed;

FIG. 13 is a top plan view of the unassembled flat blank configuration of the cover box portion of the packaging box; and,

FIG. 14 is a top plan view of the unassembled flat blank configuration of the body box portion of the packaging box. The broken lines in FIGS. 13 and 14 depict fold lines and form a part of the claimed design.
